(57) CLAIM

The ornamental design for a shoe (Calida/clo), as shown and described.

DESCRIPTION

FIG. 1 is a front perspective view of a shoe showing my shoe design;

FIG. 2 is a right side view of a shoe shown in FIG. 1;
FIG. 3 is a left side view of the shoe shown in FIG. 1; and,
FIG. 4 is a top view of the shoe shown in FIG. 1.
The broken line showing of the sole, heel, buckle, back strap, and portion of the upper is for illustrative purposes only and forms no part of the claimed design.

1 Claim, 4 Drawing Sheets
